United States Patent Office.

IMPROVED BARS OR SLATS FOR REFRIGERATORS.

JOHN C. JEWETT, OF BUFFALO, NEW YORK.

Letters Patent No. 60,523, dated December 18, 1866.

The Schedule referred to in these Letters Patent and making part of the same.

TO ALL WHOM IT MAY CONCERN:

Be it known that I, JOHN C. JEWETT, of the city of Buffalo, county of Erie, and State of New York, have invented certain new and useful improvements in Refrigerators; and I do hereby declare that the following is a full and exact description thereof, reference being had to the accompanying drawings, and to the letters of reference marked thereon.

Figure 1 is a front elevation; and

Figures 1, 2, and 3, horizontal, transverse, and longitudinal sections.

Figure 5 is a perspective view of the trap of the drip pipe; and

Figure 6, a cross-section of one of the metal-covered rack-bars.

My invention relates to the construction of the bars or slats which are used to form the ice-racks of refrigerators, and consists in making them of wood, sheathed with zinc or other sheet metal, the joints of the sheathing metal being made hermetically tight by soldering or otherwise, to prevent the absorption of moisture by the enclosed wood.

As represented most clearly in fig. 6, I construct the bars of any suitable wood, which should be thoroughly seasoned, so as not to be subject to shrinkage after it is made, and of any size adapted to that of the ice-box; one inch thick by two inches in width being suitable for ordinary refrigerators. These slats, having been planed smoothly so that a close fitting of the sheathing metal may be secured, are covered with sheet zinc, galvanized iron, or other suitable metal, rolled, pressed, or otherwise shaped to closely fit the wooden slat, covering not only the sides and edges, but also the ends in this manner. I prefer to apply the sheathing in two strips, each being first formed in the shape of a trough; so that when the two are applied the edges of one overlap those of the other, and thus form a double thickness of the sheet metal, *ff*, at the edges of the bars, by which their strength is greatly increased. All the joints of the metal sheathing are then soldered so as to exclude water from entering and being absorbed by the pores of the wood. By this construction, I secure several important advantages. First, as regards strength and lightness. The sheathing of metal surrounding the wooden bar forms a square or rectangular tube, a form which in itself possesses great strength, which is much increased in this case by the interior space being compactly filled by wood, which not only adds its own inherent stiffness, but prevents the metal from springing or warping under a strain. The resistance of the metal is doubled, also, at each end of the bar by doubling the thickness, the two being soldered together so as really to form but one. Secondly, the metal covering prevents the wood from absorbing moisture from the drippings of the melting ice, and thus obviates a very serious objection to wooden slats, that of their becoming sour and mouldy from being kept constantly wet, and thus rendering the atmosphere within the refrigerator impure. Thirdly, the metal prevents the marring and injuring of the fibres of the wood by the corners and edges of the ice-blocks falling upon them, while bars formed in this manner are much lighter, and more conveniently handled and removed than those of metal entire, if made heavy enough to resist the strain brought upon them by large masses of ice.

What I claim as my invention, is—

The construction of ice-racks, for refrigerators, of bars of wood sheathed and hermetically enclosed in zinc or other sheet metal, substantially in the manner and for the purposes herein set forth.

JNO. C. JEWETT.
